UNITED STATES PATENT OFFICE.

VINCENT BENDIX, OF CHICAGO, ILLINOIS.

ENGINE-STARTER.

1,256,102.

Specification of Letters Patent. Patented Feb. 12, 1918.

Application filed March 10, 1917. Serial No. 153,810.

To all whom it may concern:

Be it known that I, VINCENT BENDIX, a citizen of the United States, residing at Chicago, in the county of Cook and State 5 of Illinois, have invented certain new and useful Improvements in Engine-Starters, of which the following is a specification.

My invention relates to that type of engine starter exemplified in patents heretofore issued to me, for instance Patent No. 1,125,935, dated January 26, 1915, and Patent No. 1,172,864, dated February 22, 1916 which starters are characterized by a prime mover such as an electric motor and a transmission or drive for transmitting the power of the motor by means of a rotatable screw shaft and a pinion mounted thereon, to a member of the engine to be started, such as the fly wheel thereof. This drive comprises a screw shaft operated either directly or indirectly by the motor and a pinion screw-threaded on such shaft and having longitudinal movement thereon and rotary movement therewith.

My invention pertains to means for preventing creeping movement of the pinion on the screw shaft due to vibration of the automobile on which my engine starters are commonly employed, such means being arranged to prevent any possible slight rotation of the pinion which might advance it into contact with the fly wheel and thereby cause a clashing and a rasping sound, such means being so designed as not to interfere in any manner with the ordinary or normal operations of the drive.

In the drawing Figure 1 is an elevation, partly in section, of a drive embodying my invention; Fig. 2 a section on the line 2—2 of Fig. 1; Fig. 3 a detailed sectional elevation of the screw shaft and pinion; Fig. 4 an elevation of the plunger; Fig. 5 a cross section of the screw shaft and pinion illustrating a modified form of construction; and Fig. 6 a detailed view of such modified form.

The general construction of the drive is the same as shown in my patents aforesaid and therefore it will be sufficient to say that the drive comprises in connection with the extended armature shaft 1 of the electric motor indicated at A, a rotatable hollow screw shaft 2, pinion 3 adapted to mesh with the teeth of the engine fly wheel B, a coiled spring 4 constituting the yielding driving connection between the collar 5

which is secured to the armature shaft by the pin or bolt 6, and the bolt or stud 7 screwing into the enlargement 2^a of the screw shaft.

The means provided for preventing possibility of rotary movement of the pinion 3 on the screw shaft due to vibration and a consequent creeping of the pinion therewith consists of a spring-controlled device 65 carried by the pinion and coöperating with the screw shaft for normally holding such pinion in its home or retracted position but without interfering with the proper operation and action of such pinion.

Referring to the construction shown in Figs. 1 to 4, the pinion is provided with a disk 8 secured to one end thereof and having on its outer face a semi-cylindrical weight portion 8^a. This weight portion is 75 provided with a vertical hole 8^b in which slides the stem of a plunger 9. This plunger has at its inner end a head or enlargement 9^a between which and the inner face of the weight portion 8^a is a spring 10 80 coiled around such stem. This plunger is thereby spring-pressed inwardly toward and against the screw shaft and coöperates therewith to hold the pinion in its retracted position. It will be understood that this 85 spring 10 is very light and gives small resistance, which is sufficient to prevent creeping of the pinion to, but does not, interfere in any way with the normal operation of the drive. While the screw shaft may be 90 formed in different ways to thus coöperate with this plunger, I prefer the construction shown according to which the screw shaft has at the left of the screw threads a circumferential groove 2^b from which leads the 95 inclined or beveled portion 2^c on which the head of the plunger will ride when the pinion is being advanced longitudinally of the screw shaft in its normal operation.

The home position of the pinion is indicated in Fig. 1 at which time the head of the plunger is in contact with the groove 2^b. The creeping of the pinion involves a slight slow rotation thereof upon the screw shaft when stationary or a slow longitudinal movement of the pinion on the screw shaft when caused to slowly turn by vibration, or the pinion may have a combination of both of these movements, but any such movement of the pinion is prevented inasmuch as the plunger by its contact with the screw shaft tends to hold the pinion against

longitudinal movement, besides which the frictional resistance of the plunger is increased whenever the head of the pinion starts to ride upon the inclined portion 2^c, 5 thereby compressing the spring 10 and increasing the resistance and pressure afforded thereby. In the regular rapid rotation of the pinion the centrifugal force throws the plunger outwardly until stopped by the 10 compression of the spring 10.

Obviously, any recess in the shaft coöperating with the plunger would accomplish the same result but for manufacturing purposes, the circumferential groove is preferred. 15

In the normal operation of the drive, in which case the screw shaft 2 is rotated by the electric motor the pinion will be advanced longitudinally along the screw shaft 20 without any affecting resistance from the plunger, such plunger being shown in Fig. 3 as riding upon the threads of the screw shaft although it may travel between the threads.

Referring to the modified form of construction in Fig. 5 the counterbored portion of the pinion is provided with a curved leaf spring 11 secured to said pinion in suitable manner as by means of the screws 12. The 30 outer free end of this spring is inwardly kinked or curved as shown at 11^a and adapted to press against the screw shaft with a very light pressure. In order that the pinion may be retained in home position and 35 prevented from creeping movement, such shaft is provided toward its left-hand end with a groove 2^d located on the plain portion of the thread at the left-hand side of the screw threads, as indicated in Fig. 6. This 40 groove is inclined at its end adjacent the screw threads, so that the spring will easily ride out of the groove during the advance or longitudinal movement of the pinion in the regular operation of the drive. The spring 45 11 is restrained against the effect of centrifugal force by the inner face of the pinion.

In the broader aspect of my invention the disk may be considered a part of the pinion and therefore it may be properly said that 50 the spring-pressed plunger is mounted on or carried by the pinion.

I claim:

1. In an engine starter drive including a rotatable member, a driving member mounted thereon for longitudinal movement thereof and rotary movement therewith, means mounted on the driving member and adapted to contact the rotatable member and apply thereto a yielding frictional resistance 55 to prevent creeping longitudinal movement of the driving member.

2. In an engine starter drive including a rotatable member, a driving member mounted thereon for longitudinal movement thereof and rotary movement therewith, means 60 of and rotary movement therewith, means

mounted on the driving member and adapted to contact the rotatable member and apply thereto a yielding frictional resistance to prevent creeping longitudinal movement of the driving member, said latter member having a recess engaged by said means when the driving member is in its normal or home position. 70

2. In an engine starter drive including a rotatable member, a driving member mounted thereon for longitudinal movement thereof and rotary movement therewith, a spring device mounted on one of the members and coacting with the other member whereby the driving member is held in normal or 75 home position, such other member having a recess with which said device coöperates when the driving member is in said normal position.

4. In an engine starter drive including a rotatable member, a driving member mounted thereon for longitudinal movement thereof and rotary movement therewith, a spring pressed plunger mounted on one of the members and adapted to press against the other 80 member with a yielding resistance to hold the driving member in normal or home position.

5. In an engine starter drive including a rotatable member, a driving member mounted thereon for longitudinal movement thereof and rotary movement therewith, a spring pressed plunger mounted on one of the members and adapted to press against the other member with a yielding resistance to hold 85 the driving member in normal or home position, said other member having a recess with which said plunger coöperates in such 90 normal position of the rotatable member.

6. In an engine starter drive including a rotatable screw shaft, a pinion mounted thereon for longitudinal movement thereof and rotary movement therewith, friction applying means mounted on the pinion to prevent creeping longitudinal movement thereof, said means being physically independent 105 of the shaft but adapted to contact it.

7. In an engine starter drive including a rotatable screw shaft, a pinion mounted thereon for longitudinal movement thereof and rotary movement therewith, a spring pressed plunger mounted on the pinion and adapted to contact the shaft to prevent 110 creeping longitudinal movement of the pinion.

8. In an engine starter drive including a rotatable screw shaft, a pinion mounted thereon for longitudinal movement thereof and rotary movement therewith, and having at one end a projecting portion, a spring pressed plunger mounted on such pinion and adapted to contact the shaft to prevent 115 creeping longitudinal movement of the pinion.

9. In an engine starter drive including 120

- a rotatable screw shaft, a pinion mounted thereon for longitudinal movement thereof and rotary movement therewith, and having a weighted disk at one end, a spring 5 pressed plunger mounted in such disk and adapted to contact the shaft to prevent creeping longitudinal movement of the pinion.
10. In an engine starter drive including a rotatable screw shaft, a pinion mounted thereon for longitudinal movement thereof and rotary movement therewith, a spring 10 pressed plunger mounted on the pinion and adapted to contact the shaft, the shaft having a recess coöperating with the plunger when the pinion is in such normal position.
11. In an engine starter drive including a rotatable screw shaft, a pinion mounted thereon for longitudinal movement thereof 15 and rotary movement therewith, a spring 20 pressed plunger mounted on the pinion and adapted to contact the shaft, the shaft having, toward one end beyond its screw threads, a circumferential groove coöperating 25 with the plunger when the pinion is in such normal position.
12. In an engine starter drive including a rotatable screw shaft, a pinion mounted thereon for longitudinal movement thereof 30 and rotary movement therewith, a spring 35 pressed plunger mounted on the pinion and adapted to contact the shaft, the shaft having, toward one end beyond its screw threads, a circumferential groove coöperating 40 with the plunger when the pinion is in such normal position, and having its side toward the screw threads inclined.
13. In an engine starter drive including a rotatable screw shaft, a pinion mounted thereon for longitudinal movement thereof 45 and rotary movement therewith, and having a weighted disk at one end, a spring 50 pressed plunger mounted in such disk and adapted to contact the shaft, the shaft having a groove coöperating with the plunger when the pinion is in such normal position.
14. In an engine starter drive including a rotatable screw shaft, a pinion mounted thereon for longitudinal movement thereof and rotary movement therewith, friction 55 means mounted on the pinion and arranged to apply friction to the shaft in a direction radial thereof to prevent creeping longitudinal movement of the pinion.
15. In an engine starter drive including a rotatable screw shaft, a pinion mounted thereon for longitudinal movement thereof and rotary movement therewith, a spring 60 device mounted on the pinion and projecting radially toward and in contact with the shaft.
16. In an engine starter drive including a rotatable screw shaft, a pinion mounted thereon for longitudinal movement thereof and rotary movement therewith, a spring 65 pressed plunger mounted on the pinion and projecting radially toward and in contact with the shaft.

VINCENT BENDIX.
